(57) **CLAIM**

The ornamental design for a paint tray, as shown and described.

DESCRIPTION

FIG. 1 is a first perspective view of a paint tray showing my new design;

FIG. 2 is a second perspective view thereof;

FIG. 3 is a front view thereof;

FIG. 4 is a rear view thereof;

FIG. 5 is a left side view thereof;

FIG. 6 is a right side view thereof; and,

FIG. 7 is a top view thereof.

The broken lines in FIGS. 1, 6 and 7 show portions of the paint tray that form no part of the claimed design.
